ABSTRACT OF THE DISCLOSURE

Hydrocarbon feed stocks are cracked by passing them in a straight linear path through elongated externally heated tubes of open cross-section, with a residence time at about 650° C. or higher of less than 0.5 second, preferably less than about 1.4 second, a pressure drop of about 3-5 p.s.i. per tube, and a tube skin temperature of about 1000°-1200° C.

BRIEF SUMMARY OF THE INVENTION

This invention relates to a cracking of hydrocarbon feed stocks and more particularly to a straight-through hydrocarbon cracking apparatus and process which produces a product having enhanced ethylene content.

BACKGROUND OF THE INVENTION

(a) Field of the invention

This invention lies in the field of hydrocarbon cracking, as exemplified by the U.S. patent to Kitzen No. 3,535,920, granted Nov. 21, 1967.

(b) Description of the prior art

Reference is made to the patent to Kitzen No. 3,535,920, granted Nov. 21, 1967. It is known that hydrocarbon cracking furnaces and processes have involved the use of conventional operating conditions for a sufficient time to reach substantially equilibrium conditions for recovery. The Kitzen patent taught that better results can be obtained on some cases by using especially severe conditions of temperature and heat input, and by then cutting off the reaction prior to the time that equilibrium is reached.

The Kitzen patent points out that various problems are overcome, when using a furnace having tubes arranged in a serpentine or coiled path, by using the so-called "high severity" process, in which the reactants are treated severely and then quenched before they have a chance to reach equilibrium conditions.

The use of coils in a high severity type furnace has always been considered highly advantageous because these coils present maximum exposure to heat exchange surface to the source of heat, and provide maximum dwell time for the reactants in the furnace because of the tortuous nature of the path through which the reactants flow.

SUMMARY OF THE INVENTION

It has now been discovered that substantially enhanced ethylene contents can be obtained in the product, and that other advantages are achieved as well, by conducting the cracking operation in a furnace having a multiplicity of essentially straight elongated tubes which have completely free cross-sections, by passing the feed stock in a substantially straight linear path through one of these tubes, and establishing a high velocity of feed and withdrawal in order to provide a very low material residence time at a temperature above about 650° C. in the tubes of less than about 0.5 second, preferably only about 1.4 second, maintaining a total pressure drop in the tube from inlet to outlet of about 0.3-5 p.s.i., maintain-

2

ing a tube skin temperature of about 1000-1200° C., and suddenly quenching the reaction product as it emerges from the tube, long before the reactants have a chance to come to equilibrium.

5 BRIEF DESCRIPTION OF THE DRAWINGS

FIG. 1 shows, in side elevation, a typical straight through furnace which embodies features of this invention.

FIG. 2 represents a tube skin temperature profile curve, taken at various points along the lengths of the furnace tubes during actual furnace operation.

DETAILED DESCRIPTION OF THE DRAWINGS

The furnace shown in the drawing has a plurality of elongated straight tubes 10, extending vertically through the combustion zone 11 of the furnace 12. Heat is provided by a multiplicity of spaced apart burners B located on the inner surfaces of the furnace walls 13. Preferably the burners B are located on both opposed front and back walls of the furnace, in a manner to direct heat at opposite faces of each tube. The feed materials are introduced into the upper header 14 and are withdrawn through lower header 15 and pipe 16, to quench.

It has been found that, in a furnace provided with a multiplicity of parallel, straight tubes arranged in vertical relationship with one another, with burners in the opposed walls of the furnace, it is possible to obtain substantially equal and uniform tube skin temperature profiles in all the tubes. This arrangement of the combustion components and the straight-through path of the material provides excellent duplication from tube to tube with a resulting profile which is considered to be unique in the art.

It is to be emphasized that the tubes in accordance with this invention are straight-through, and are arranged to carry the reaction products once through, and only once, and that the tubes all have open cross-sections. They are not filled with catalysts or any other solid materials, such as the tubes that are referred to in the patent to Fleischer No. 3,062,167, assigned to the assignee hereof.

Preferably, the tubes are subjected to controlled heating so that the inner wall temperature of each tube is substantially constant from one end of the tube to the other. This is accomplished by the spaced arrangement of the radiant heat burners B and by providing variable firing rate equipment for each burner, along with control means for controlling each firing rate, the latter being well known per se.

This invention is to be distinguished sharply from the use of serpentine tubes as in the aforementioned Kitzen Pat. No. 3,535,920. It has been found that serpentine tubes provide at least three times as much pressure drop, largely because of the bends, and that great operating improvements are surprisingly obtained in a once-through straight line system according to this invention.

The following table illustrates typical differences between a conventional high severity furnace in accordance with the Kitzen patent, and a straight-through furnace in accordance with this invention.

60	High severity:	Straight-through
	25% ethylene product	25% ethylene product.
	Outlet tube temperature	
	850° C.	Outlet temperature 800° C.
	Tube skin temperature	
	950° C.	Tube skin temperature 1050° C.
	Methane yield 16%	Methane yield 14%.

EXAMPLE 1

70 A full series of tests was conducted, using a "full range" naphtha, at a predetermined throughput rate and at outlet temperatures varying between 740° C. and 840° C.

The results of these tests appear in the table which follows.

During all tests the input was according to the design of the furnace, namely, 2.7 metric tons per hour of

tubes being about 35 feet long. Before the series of tests was started the furnace was decoked completely and several runs were obtained with the product outlet temperature at the exit from the tubes varying from 740° C. to 840° C. In all cases, the outlet header was located within the furnace area. Typical parameters of the feed stock are given below.

	Run Number	
	33	36

FBP	135	145

The number of burners B in operation was varied from 40 (during run 33) to 48 (during run 44), all burners operating at equal burner pressure of approximately 1 atmosphere and burner banks on both sides of the tubes being fired. At the bottom rows, near the outlet, no burners were used except during runs 42 and 43 when two burners were used for each run. When the tube skin temperature approached the maximum allowable temperature of about 1200° C., the two burners at the bottom rows were shut off during run 44. The average actual temperature profiles taken along the lengths of the tubes are shown in FIG. 2 of the drawings. In every case, the material residence time in the tubes, during which the material was at a temperature of 650° C. or above, was less than 0.5 second and even in the range of 0.1–0.4 second.

EXAMPLE 3

Another set of runs was conducted. Again before the series was started the furnace was decoked. The furnace outlet temperature was varied from 700° C. to 770° C., at design gas oil input and 67% dilution with steam.

The characteristics of the gas oil feed stock were as follows:

"Tube skin temperature" as referred to herein is intended to indicate the temperature measured at the out-

In all of these runs, the material residence time as herein defined was less than 0.4 second. The results show that optimum conversion for by-product yields is at about 780° C. to 800° C. and that at higher temperatures ethylene yield is still increasing, however, at the cost of propylene and C₄ production.

The reduced methane yield is advantageous because methane is much less desirable as a product than ethylene or propylene.

In accordance with the preferred embodiment of this invention, steam is introduced with the hydrocarbon feed for the purpose of dilution. Approximately .3-1.0 pound of steam per pound of hydrocarbon feed are used. The steam helps to keep the coking low and keeps the partial pressure of hydrocarbon feed low.

heat to the tubes of the outlet portions than at the inlet portions. This tends to provide a substantially constant tube wall temperature from end to end.

The pressure drop from the inlet to the outlet of the tube in accordance with this invention is less than about 5 p.s.i. gauge for a typical tube that is about 35 feet long. Tubes can be from 20'-60' in length depending upon process requirements.

As stated, it is important to provide a quench at the outlet end of the tube. This is done by conventional quenching means well known in the art and not shown in the drawing.

It will be appreciated that the amount of the pressure drop varies from tube to tube and depends among other things upon the inside diameter of the tube. For a rather

small size commercial tube having an inside diameter of 3.21 inch, a pressure drop of 0.5 p.s.i. has been measured. However, the pressure drop can go up to as high as about 2 p.s.i. during the operation of the apparatus, particularly if some coking is experienced after an extended period of operation.

It will also be appreciated that the hydrocarbon partial pressure changes as the reaction proceeds and also varies depending upon the amount of dilution steam that is incorporated into the feed. An increased dilution proportion produces more olefins and less methane in the product.

The feed stock in accordance with this invention can be essentially any feed stock which is known to be useful for the production of olefins such as ethylene and the like, and includes all the feed stocks referred to in the aforementioned Kitzen Pat. No. 3,353,920. Typical of such feed stocks are gas oils, naphtha, liquid petroleum gas feeds, ethane, propane, butane, etc.

Although this invention has been described with reference to a specific form thereof, it will be appreciated that other variations may be made without departing from the spirit and scope of the invention.

The following is claimed:

1. In a method of cracking a hydrocarbon feed stock, the steps which comprise feeding said stock in a substantially straight linear path through an elongated tube, maintaining said linear path free of any obstruction, establishing a velocity of feed and a velocity of withdrawal of product, to provide a material residence time in the tube at a temperature above about 650° C. of less than about 0.5 second, maintaining a total pressure drop in the tube

from inlet to outlet of about 0.3-5 p.s.i., maintaining a tube skin temperature of about 1000-1200° C. and suddenly quenching the reaction product as it emerges from the tube.

5 2. The method defined in claim 1, wherein the feed is diluted with about .3 to 1.0 pound of steam per pound of hydrocarbon.

3. The method defined in claim 1, wherein the tube skin temperature is about 1050° C.

10 4. The method defined in claim 1, wherein the product temperature as it leaves the tube is maintained at about 740-840° C.

15 5. The method defined in claim 1, wherein the residence time of the material in the tube is about .0-.4 second and the product temperature as it leaves the tube is maintained at about 780-800° C.

6. The method defined in claim 1, wherein the tube is subjected to controlled heating so that the inner wall temperature of the tube is substantially constant from one end of the tube to the other end of the tube.
